ELECTRICAL SIGNAL DISTRIBUTION SYSTEM

Edward Arthur Newman, Teddington, Donald Watts Davies, Southsea, and Ronald Fraser Braybrook, South Kensington, London, England, assignors to National Research Development Corporation, London, England, a British corporation

Application February 8, 1951, Serial No. 209,946
In Great Britain February 28, 1950

7 Claims. (Cl. 250—27)

1

This invention relates to distribution circuits that is to say circuits adapted to open (or close) one of 2^n channels in accordance with a particular permutation of polarities, of n voltages applied to the circuit.

Such circuits are used for example in digital computing systems for selecting channels in accordance with numbers in instruction words and an example of a distribution circuit and its method of operation is described in United States patent application No. 202,615 by James H. Wilkinson, filed December 26, 1950, with reference to Figure 15 of the drawings of that specification. These circuits are also described on pages 40 to 43 and 377 to 378 in "High-Speed Computing Devices" written by the Staff of Engineering Research Associates and published in 1950 by McGraw-Hill Book Company.

Distribution circuits generally comprise a network of resistances, usually called a matrix or distribution matrix, to which voltages are applied to yield on the output leads various voltages of which one (on the output lead selected by the permutation of the polarities of the input voltages) is greater than any of the others. In the usual network of equal resistances if each applied voltage is V it can be shown that the voltage on the selected output lead is V while the highest voltage on certain other output lines is $V(1-1/n)$, where n is the order of the matrix. Thus the "discrimination factor" of the matrix is $1/n$.

For example in a matrix of order five if the applied potential differences are each 30 volts then the voltage on the selected output line will be 30 volts the highest voltages occurring on certain other output lines will be 24 volts, giving 6 volts discrimination.

It is not convenient to have a series of lines with various voltages on them for controlling a series of gates and the present invention is concerned with an output circuit for a matrix which will give one predetermined voltage on a selected output and another predetermined voltage on all the remaining outputs.

The invention also provides a circuit which depends for its operation on the difference in potential between the selected output line from the matrix and the output lines of next highest potential and thus overcomes to a great extent irregularities in operation due to variations in the voltages applied to the input of the matrix circuit and to slight non-uniformity in the resistances in the matrix itself.

According to the present invention, there is provided an output circuit arrangement for a

2

distribution circuit and comprising a series of thermionic valves having separate anode loads and input circuits but a common cathode load, the valves being arranged to be controlled separately at their input circuits by the output voltages from a matrix circuit so that only one selected valve in the series passes anode current when the distribution circuit is set up.

The common cathode load may be a simple resistance but when the matrix is used in a computing system it is convenient to render it operative only during certain periods. According to a feature of the invention, therefore, the common cathode load comprises a further thermionic valve circuit arranged to be conductive only when the distribution circuit is required to operate.

The invention will now be described with reference to the accompanying drawings of which:

Figure 1 illustrates one embodiment of the invention and

Figure 2 illustrates a detail of a modified embodiment of the invention.

In Figure 1, there is shown a matrix 1 of order n the output leads of which feed the control grids of 2^n (or as many as there are circuits to be controlled by the matrix) valves of which three are shown at 2, 3 and 4. The cathodes of all valves such as 2, 3 and 4, are connected through a common load 5 to a source of low potential, say -300 volts. As indicated, this load may be a resistance. The valves such as 2, 3 and 4 are connected through separate anode loads to a source of high potential, say +300 volts.

When working with very short duration pulses, the anode loads and coupling circuits of the various valves may require the usual de-coupling and correcting impedances. Thus the anode loads of the valves such as 2, 3 and 4 may each comprise, as shown in the drawing, 360 microhenries in series with 4,700 ohms and 22,000 ohms, which is in parallel with 0.01 microfarad.

Suppose now that the inputs to the matrix 1 are such that the potential of the grid of valve 2 is somewhere near earth potential, and is greater than the potential on the control grid of any of the valves by a potential sufficient to cut the valves off, then valve 2 alone will be conducting and its anode potential will be at some predetermined level while the anode of all the other valves will be at some predetermined higher level.

The series of valves such as 2, 3 and 4 feed a corresponding series of gate circuits from their anodes and the gate circuit associated with the valve 2 is shown at 9, the other gates are omitted from the picture for the sake of clarity.

A suitable gate circuit 9 comprises two valves 10 and 11 having a common cathode resistance connected to a source of negative bias of 300 volts. The anode of valve 11 is connected to earth and the grid thereof is connected to the anode of valve 2 through resistance 30 and capacitance 31 in parallel and to a bias of -300 volts through resistance 14. The cathodes of valves 15 and 16 are connected to the anode of valve 10 and the grids of these valves are respectively potentials of 0 and +7 volts. The anodes of valves 15 and 16 are biased at +200 volts.

If, then, a signal of +15 volts is applied to the grid of valve 15 at the time valve 10 is made conducting due to the application of a negative pulse from valve 2 to the grid of valve 11, a current will flow through valve 15 and an output pulse will be transmitted from the anode of valve 15.

The gate 9 is fed by the valve 2 through a resistance of 470,000 ohms in parallel with 470 micromicrofarads to match the anode load of the valve.

In one particular embodiment of the invention the valves had a grid base of about 4 volts and the various resistances and supply potentials were arranged to give the working potentials indicated in the drawings.

The common cathode load 5 may be a simple resistance but in some uses of the invention it may be convenient to replace this resistance by a circuit which becomes conducting only during certain periods. Such a circuit is shown in Figure 2. This circuit comprises two valves 17 and 18 having separate anode circuits but a common cathode load 19 leading to a point of low potential, say -300 volts. The control grid of the valve 18 is held at, say -200 volts while the control grid of the valve 17, is normally held at -210 volts but is caused to rise to -190 volts and so to become conducting during periods in which the matrix circuit is to operate. The output circuit in Figure 1 forms the anode load of the valve 17 and thus becomes operative only when valve 17 is conducting.

The circuit as so far described is suitable for switching the matrix output circuit in most cases but when the pulses to be dealt with occur at a very high frequency (e. g. $\frac{1}{2}$ microsecond pulses occurring at a repetition frequency of a megacycle) two further valves 20 and 21 may be used. These valves 20 and 21 have their cathodes and grids connected and controlled in the same manner as the valves 17 and 18 but have in their anode circuits inductive loads 22 and 23 which give sharp negative and positive voltage peaks as the valves 20 and 21 are switched on and off. The inductive loads 22 and 23 may be shunted by resistances (as shown) to control the amplitude and attenuation of the voltage peaks.

These voltage peaks are applied to two valves 24 and 25 biassed to be operated by the positive-going peaks only. The valve 25 is a cathode follower and applies the positive peak (the "off" peak) from the valve 20 as a positive voltage pulse to the common cathodes in the matrix output circuit of Figure 1. The actual value of the grid-bias potential on valve 25 will depend, of course, on the mean value of the cathode potentials of the valves such as 2, 3 and 4 in Figure 1. The valve 24 is connected normally and applies the positive peak (the "on" peak) from the valve 21 as a negative voltage pulse to the common cathodes of the matrix output circuit.

What we claim is:

1. An electrical signal distribution system com-

prising a distribution matrix having a plurality of outputs, a plurality of thermionic valves having individual output circuits and individual grid circuits but a common cathode load, means connecting each of said matrix outputs to a respective individual grid circuit of one of the thermionic valves, and a gating circuit connected to the individual outputs of each valve, each gating circuit including thermionic valve means responsive to voltage changes in the said output to which the gating circuit is connected.

2. An electrical signal distribution system as claimed by claim 1 wherein the gating circuit includes a first and a second thermionic valve, the grid of the first valve being connected to the said individual output and the anode of the first valve being connected to earth and the cathodes of both valves being connected to a common bias source; a third and a fourth thermionic valve having their cathodes connected to the anode of the second valve, the grid of the third valve having a small positive bias impressed thereon and means connected to the anode of the fourth valve to transmit a signal in response to a signal impressed on the grid of the fourth valve at a time when the second valve is conducting due to the application of a negative pulse to the grid of the first valve.

3. An electrical signal distribution system as claimed by claim 1 wherein the common cathode load includes a plurality of thermionic devices connected to become conductive and make the cathode load operative in response to a signal applied thereto simultaneously with the application of a signal to the matrix.

4. An electrical signal distribution system comprising a matrix having a plurality of outputs, a respective thermionic valve connected to each output, gating circuitry connected to each valve to be readied for signal transfer by a voltage applied thereto from the valve when the valve is conducting; and a common cathode load for all the said valves, the said load including first and second paired thermionic valves each having anode, grid and cathode, the first anode being connected to the cathodes of the valves connected to the matrix outputs, the second anode being grounded, the two cathodes having a common connection to a source of considerable negative potential, the grids being at a less negative potential than the cathodes and the second grid being somewhat less negative than the first grid, whereby the second valve will normally be conductive; third and fourth paired thermionic valves each having anode, grid and cathode, both the third and fourth anodes being grounded, the cathodes being at the same negative potential as the first and second cathodes, and the third and fourth grids being at the same potentials as the first and second grids, respectively, and like impedances connected between each of the third and fourth anodes and ground; a fifth thermionic tube having anode, grid and cathode, there being a small negative bias on the fifth grid, means connecting the fifth grid to a point between the third anode and its associated impedance, and means connecting the fifth cathode to the cathodes of the valves connected to the matrix outputs; a sixth thermionic valve having anode, grid and cathode, there being a small negative bias on the sixth grid, means connecting the sixth grid to a point between the fourth anode and its associated impedance, the sixth cathode being grounded, an impedance connected to the sixth anode and means connecting the sixth anode to

60

75

the cathodes of the valves connected to the matrix outputs.

5. An electrical signal distribution system comprising a matrix having a plurality of outputs, and means connecting each of said outputs to the grid of a respective first thermionic valve having anode, grid and cathode, an anode input impedance; second and third paired thermionic valves each having anode, grid and cathode, the cathodes being connected through a common cathode load to a source of large negative bias, the two grids being at negative potentials less than that of the source of cathode bias and the second grid being somewhat less negative than the third grid, the second anode being grounded whereby the second valve will normally be conductive and the bias on the cathodes will be higher by a value equal to the drop across the cathode impedance than the potential of the source to which they are connected; fourth and fifth thermionic valves each having anode, grid and cathode, common means connecting the fourth and fifth cathodes to the anode of the third valve, the fourth and fifth anodes having strong positive bias impressed thereon, the grid of the fourth valve being somewhat more positive than that of the fifth valve so that when the third valve is conducting the fourth valve will also conduct but the fifth valve will become conductive when a positive signal voltage higher than the bias on the fourth grid is impressed upon the fifth grid; means connecting the grid of the second valve to a point between the anode and the anode impedance of the first valve whereby when said first valve conducts the grid of the second valve is made more negative so that the third valve becomes conductive; and a common cathode load for all the valves connected to the matrix outputs.

6. An electrical signal distribution system, comprising a plurality of like thermionic valves, means selectively to place any one of said valves in conducting condition; gating circuitry operatively associated with each of said valves, the gating circuitry having a first pair of triode thermionic valves, a common connection to the cathodes of the valves of this pair; a second pair of triode thermionic valves having their cathodes connected in common to the anode of a valve of the first pair, the anode of the other valve in the first pair being grounded, and means connecting the grid of said other valve in the first pair to the anode of a respectively associated valve of said plurality; and a common cathode load for all the valves of said plurality, including a third pair of triode thermionic valves having a common connection to their cathodes, the anode of one valve of the third pair being

connected to ground and the other anode of the third pair connected in common to the cathodes of all the valves of said plurality, a fourth pair of triode thermionic valves having a common connection to their cathodes and a peaking impedance connected to each anode and to ground, a cathode follower valve having its cathode connected to all the cathodes of said plurality of valves and means connecting its grid to a point between the anode and the peaking impedance of one valve of the fourth pair, and a thermionic valve having its cathode grounded, means connecting the grid of the last-mentioned valve to a point between the anode and the peaking impedance of the other valve of the fourth pair, an anode impedance connected to the anode of the last mentioned valve, and means connecting all the cathodes of the valves of said plurality to the anode of the last-mentioned valve.

7. An electrical signal distribution system, comprising a plurality of like thermionic valves, means selectively to place any one of said valves in conducting condition; respective gating circuitry responsive to a signal from each of the valves of the plurality, each circuitry having a first pair of triode thermionic valves, a common connection to the cathodes of the valves of this pair; a second pair of triode thermionic valves having their cathodes connected in common to the anode of a valve of the first pair, the anode of the other valve in the first pair being grounded, and means connecting the grid of said other valve in the first pair to the anode of the respective valve in the said plurality; and a common cathode load for all the valves of the plurality, including a third pair of triode thermionic valves having a common connection to their cathodes, the anode of one valve of the third pair being connected to ground and the other anode of the third pair connected in common to the cathodes of all the valves of said plurality.
